CLAIM

The ornamental design for a kickstand case for mobile phone, as shown and described.

DESCRIPTION

FIG. 1 is a front, left, and top perspective view of a kickstand case for mobile phone, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a knob.

FIG. 10 is a partial enlarged view of an area labeled 10 in FIG. 1 comprising a part of a stand; and,

FIG. 11 is another front, left, and top perspective view of the kickstand case for mobile phone of FIG. 1, wherein a stand of the kickstand case for mobile phone is in a folded state. The broken lines shown in the drawings are included for the purpose of illustrating portions of the kickstand case for mobile phone that form no part of the claimed design.
